UNITED STATES PATENT OFFICE.

JOHN H. SAYRES, OF BROOKLYN, NEW YORK.

LATCH-CONTROLLED OPERATING MECHANISM.

Application filed January 22, 1926. Serial No. 83,162.

My invention consists of an operating mechanism which is latch controlled, preferably of the type wherein an electric contact and electrical connections serve to operate a trip mechanism.

Among the objects of my invention may be mentioned:

(1) The use of an electric current or other convenient means to release a strong mechanical operating force;

(2) The use of remote control contacts automatically controlling the operation of the mechanism;

(3) The use of a minimum of current or other power, i. e., for only the instant of time required to actuate the mechanism;

(4) Immediate breaking of the actuating current or shut off of other actuating means as the mechanism acts, thus eliminating waste, inconvenience to the operatives, or danger of igniting materials;

(5) An improved and very sensitive toggle mechanism trip to release the heavy mechanical force, while nevertheless being itself controlled by the relatively small pull of, say, an electro-magnet.

Other objects will be apparent upon consideration of this specification.

I have discovered that these objects are best attained by means of an electromagnet actuating an armature which trips one end of a series of linked toggles. A preferred form of my invention is illustrated in the accompanying drawings in which:

Figure 1 is a diagrammatic sketch of a form of my invention wherein a normally open electric circuit upon being closed trips the releasing means.

Fig. 2 is a diagrammatic sketch of the normally closed circuit modification.

Fig. 3 is a perspective sketch of the complete apparatus, in which an alternative form of the reset spring is shown.

Referring briefly to the construction, the essential features of the mechanism are:

(1) A displaceable operating member such as the rod 11;

(2) Some means for stressing and, upon release, actuating the displaceable operating member, as the spring 12; together with

(3) A releasable detaining mechanism to which the invention particularly refers.

This mechanism comprises a latch adapted to detain the operating member against the stressing force, as here shown (for example,

by means of a member 14 adapted to engage a notch 15 in the rod) together with a releasing mechanism comprising a toggle train, (for example, the members 16, 21, 23, 25 and 27) the final member cooperating with a trip member (such as the armature 28). Preferably the trip member is operated automatically as by an electromagnet. The trip member may be operated by hand, in fact it is usually desirable to have manually operated tripping means in combination with the automatic means.

Heretofore mechanisms of the class embracing my invention have usually depended upon battery current or upon small generators to supply the energy required for tripping the system. Batteries are frequently found exhausted at the critical moment, and generators of an economical size can not always be relied upon to give sufficient current.

While my invention may be operated on battery or generator current if desired, it is designed primarily for operation on ordinary power or lighting circuits, utilizing the cold resistance of a metal filament lamp. In the well known Mazda lamp this cold resistance is about 1/14 of the hot or light resistance. A circuit breaker stops the current as soon as the mechanism has begun to release, thus insuring a flush of current, instantaneous only, and so powerful that there is never any question of 100% operation. Another advantage of the use of a metal filament lamp for operating on its cold resistance is that it permits the use of a much heavier and more mechanically durable magnet wire than would be possible were high resistance wires used.

Other features of my invention preferably include a hand stop entirely independent of the electrical connections, and the use of enamelled wire for the magnets. This wire has proved itself to be entirely free from insulation troubles.

Referring now more particularly to the drawings, and especially to Figure 1, a mechanism housing 10 has slidably running through it a knockout rod 11, the motion of which is employed to accomplish the purposes of the mechanism. A spring 12 rests upon one face of the mechanism housing 10 and stresses the knockout rod by exerting a force against a collar 13 rigid with the knockout rod. The force exerted by the

spring tends to move the rod away from the mechanism housing in the direction indicated by the arrow X. Such motion is prevented by the action of a latch 14 which sits in a notch 15 in the knockout rod.

The latch 14 is held in place and tripped by an especially designed toggle mechanism and tripping means which will now be described.

10 The latch 14 is attached to the end of a lever 16 which is pivoted near its midpoint to a fulcrum rod 18 by a pin 17, and is free to teeter about that point. The fulcrum rod 18 is in turn pivoted by means 15 of a pin 19, to the mechanism housing.

At the end farthest from the latch a pin 20 connects the lever 16 with the lever 21, which is in turn pivotally connected with the mechanism housing at its other end by the pin 22. Also connected with the lever 16 and the lever 21 by the pin 20 is the toggle arm 23, which is connected at its other end by a pin 24 to its coacting toggle arm 25. The toggle arm 25 is pivoted at 25 its far end to the mechanism housing by the pin 26. Two coacting toggles are thus seen to exist: one formed by the levers 16 and 21, pivoted at 20, and one consisting of the toggle arms 23 and 25 pivoted at 30 24, the common pivot being at 20.

When in the positions shown in the full lines in Figures 1 and 2 this toggle system holds the latch 14 in engagement with the knockout rod and thus prevents its displacement by the stress resulting from the force of the spring 12.

The toggle system—and with it the latch—is held in position by means of a member 27, rigid with the toggle arm 25. 40 This member 27 is engaged and held in position by a lever 28, which is pivoted to the mechanism housing by the pin 29. The lever 28 is the armature of an electromagnet 30, and is adapted to be pulled thereby out of engagement with the member 27. A spring 31, here shown as a leaf spring, normally holds the armature 28 away from the electromagnet 30.

From a consideration of the preceding 50 description and the drawings it is evident that a small force applied by the armature 28 against the end of the member 27 will balance a large force exerted by the notch 15 upon the latch 14. It is also apparent that by energizing the electromagnet 30, the armature 28 is drawn against the electromagnet and out of engagement with the member 27, thus tripping the system and releasing the latch. The members then assume the positions shown in dotted lines.

The electric circuit which energizes the electromagnet is indicated as starting at a source of power 32, travelling through a wire 33 to contact points 34, ordinarily external to and frequently at a considerable

distance from the device. A wire 35 connects the contact points with a Mazda lamp 36, whence another wire 37 connects with a circuit breaker 38 rigidly attached to the latch 14. The circuit breaker 38 is connected to the electromagnet 30 by a wire 39 and a wire 40 completes the circuit to the source of current 32.

For moving the armature 28 out of engagement with the member 27 and tripping the system, I also provide a hand stop 41, which acts through a rod 42 and a bracket 43, upon a bracket 44, rigidly attached to the armature 28. By reference to Figure 1 it will be apparent that by pressing the hand stop 41, the armature 28 is brought against the electromagnet exactly as if the magnet had been energized. Naturally, the other elements will also act as they would had the magnet been energized.

55 In addition to the notch 15 the rod 11 is notched at 45 to coact with a member 46 which is a part of the toggle member 25. After the rod 11 has performed its function as a knockout and is being reset to its latched position a spring 47 acting through a rod 48 pulls toggle member 25 to a point where member 46 can be engaged by notch 45. Thereafter the further movement of the rod 11 in a direction opposite to that of the 60 arrow X pushes toggle member 25 into its normal position. In the full reset position spring 47 lies loose and without tendency to produce motion in toggles 23, 25. The reason for this is to avoid resisting the breakage of toggles 23, 25 at pin 24 when the external contact points 34 close. It will be apparent that a very small transverse force such as spring 47 acting on pin 24 would resist a very heavy external spring 12, the purpose 65 of which is to operate the knockout bar. As soon as toggle members 23 and 25 have reached their final position, the knockout bar 11 moves slightly in the direction of arrow X until notch 15 engages with latch 14. This leaves the member 46 and toggle members 23 and 25 entirely free from transverse 70 force and permits a minimum operating 75 spring 12 much smaller than would otherwise be possible.

75 In the perspective view (Fig. 3) a double torsion spring 47^a acting upon the lower lip of the lower member of the second toggle serves to bring the reset lip into engagement with the reset notch 45.

80 I may apply the operating mechanism to a great variety of machines, which it may be desired to stop quickly and automatically in an emergency or at the end of work. In every case the emergency or end of work 85 is utilized to cause contacting of a pair of points 34, thus closing the electric circuit, energizing the electromagnet 30, and drawing the armature 28 suddenly against the electromagnet. This trips the lever 27, per-

mitting the toggles 23, 25 and 16, 21 to assume the positions indicated in the broken lines (Fig. 1). The other members then necessarily assume the broken line positions shown, the latch 14 being thrown clear of the notch 15 by the action of the spring 12, and releasing the rod which is immediately forced in the direction of the arrow X by the spring 12. At the same time the latch 10 throws the circuit breaker 38 to which it is attached. The circuit is thus broken, immediately conserving current, eliminating any possibility of sparking at the external contact points or burning out of the magnet. 15 Fire risk is thus eliminated, and the operator of the machine is able to make any corrective adjustment without danger or inconvenience from the electrical system.

While the description has been drawn to 20 a construction wherein a normally open circuit is employed, a normally closed circuit may be used equally well. In fact for some purposes a normally closed circuit is preferable. Such a mechanism is illustrated in 25 Fig. 2. The only difference between the normally open and the normally closed circuit is that while in the former the armature is pulled toward the magnet thus breaking the toggle, in the latter the armature is held 30 against the magnet, and is released when the circuit is broken, thus permitting the toggle to break in the opposite direction. No circuit breaker is needed in the normally closed circuit machine.

35 Also it is apparent that an unequal arm lever might replace one of the toggles described. It is equally obvious that some displaceable body other than a rod (say a rotatable disc) might be used.

40 It will be at once apparent that this automatic motion may be used to shift a belt, open a switch, open or close a valve, throw a clutch handle, or otherwise instantly disconnect the power driving a machine. Other 45 uses will also occur to those familiar with this type of apparatus: as, the application of brakes, opening of fire house or emergency doors, setting of signals, etc.

I have previously employed automatic 50 stop motions of a character not altogether unlike that described in my present invention, which operate by means of unequal arm levers. I make no claim to this type of apparatus, but confine myself to one in which a combination of toggles is employed.

With the understanding that the illustration herein given is merely used to indicate a preferred form of my invention, and that many modifications will naturally occur to those dealing with the problem, without, however, departing from what I claim as my invention, I claim:

1. An automatic stop mechanism comprising a rod, a lug upon said rod, a housing through which said rod passes, and a spring

compressible between said lug and said housing in combination with toggle means for holding said rod against the action of said spring, and electrical means for releasing said toggle means. 70

2. In an automatic stop mechanism, a spring and toggle means for holding said spring compressed, in combination with electrical means adapted to release said toggle means, and electrical contact points remote 75 from said toggle means.

3. In an automatic stop mechanism, a spring, and toggle means for holding said spring compressed, in combination with electrical means adapted to release the toggle 80 means, and mechanical means adapted to reset the toggle means when said spring is compressed.

4. In an automatic stop mechanism a spring, a rod and toggle means for holding 85 said spring compressed, in combination with electrical means adapted to release the toggle means, a reset lip upon an element of the toggle means, and means upon said rod for engaging said reset lip. 90

5. In an automatic stop mechanism, a spring, and toggle means for holding said spring compressed, in combination with an electromagnet adapted to release said toggle means, electrical connections, and contact 95 points remote from said electromagnet.

6. In an automatic stop mechanism, a spring, toggle means for holding said spring compressed, and electrical means for releasing said toggle means, in combination with 100 a circuit breaker adapted to be opened by the releasing action of said toggle means.

7. In an automatic stop mechanism, a spring, toggle means for holding said spring compressed, an electromagnet adapted to release said toggle means, and suitable electrical connections, in combination with an incandescent lamp in series with said electromagnet. 105

8. In an automatic stop mechanism, a 110 spring, toggle means for holding said spring compressed, an electromagnet adapted to release said toggle means, and suitable electrical connections, in combination with resistance in series with said electromagnet. 115

9. A mechanism comprising a rectilinearly movable operating bar, a spring stressing said bar in one direction, and a latch mechanism for detaining said bar against the effort of the spring, said latch mechanism comprising a latch arm one end of which operatively engages said bar, a pivoted toggle link engaging the opposite end of said latch arm, and a suspender rod connected to said latch arm intermediate its ends, together with a detent operatively associated with said latch arm and normally maintaining the latch in engagement with the operating bar. 125

10. A mechanism comprising a rectilin- 130

early movable operating bar, a spring stressing said bar in one direction, a latch mechanism for detaining said bar against the effort of the spring, said latch mechanism comprising a latch arm one end of which operatively engages said bar, a detent normally maintaining the latch in engagement with the operating bar, a swinging hanger connected to said latch arm intermediate its ends, and a pivoted toggle link engaging the opposite end of said latch arm, in combination with other toggle links, and an

electromagnet adapted to trip the toggle system.

11. In an automatic stop mechanism, an 15 electromagnet, a spring, toggle means for holding said spring compressed, and a circuit breaker operated by said electromagnet, in combination with a metal filament lamp used as resistance in series with the windings 20 of said electromagnet.

In testimony whereof I have signed my name to this specification.

JOHN H. SAYRES.
